United States Patent Office.

D. M. ESTEY, OF BRATTLEBOROUGH, VERMONT.

Letters Patent No. 96,787, dated November 16, 1869.

IMPROVED BEDSTEAD.

The Schedule referred to in these Letters Patent and making part of the same.

To all whom it may concern:

Be it known that I, D. M. ESTEY, of Brattleborough, in the county of Windham, and State of Vermont, have invented a new and useful Improvement in Bedsteads; and I do hereby declare that the following is a full, clear, and exact description thereof, which will enable others skilled in the art to make and use the same, reference being had to the accompanying drawing, forming part of this specification, in which—

Figure 1 is a top view of a bedstead, illustrating my invention, part of the rails being broken away to show the construction.

Figure 2 is a detail sectional view of the same, taken through the line *x-x*, fig. 1.

Similar letters of reference indicate corresponding parts.

My invention has for its object to so improve the construction of bedsteads that the slats may be secured in place without the use of ledges or strips attached to the inner sides of the rails, and which shall at the same time allow the said slats to be conveniently taken out and put in when required; and

It consists in the manner in which the slats are connected with the rails of the bedstead, as herein-after more fully described.

A represents the posts, *B* the end rails, and *C* the side rails, which parts are connected to each other in the ordinary manner.

In the inner side of one of the rails of the bedstead are formed grooves *D*, of such size as to receive the ends of the slats *E*, and of such a depth as to give a firm support to the ends of the said slats, said grooves being formed in such positions as not to mar or disfigure the edges of said rails.

The slots or grooves *D* in one rail are formed only

of sufficient length to receive the ends of the slats, but the grooves *D'* in the other rail are lengthened at one end, so as to gradually decrease in depth till they come to the surface of the rail, as shown in figs. 1 and 2, thus allowing the slats to be conveniently inserted and removed.

The slots *D'* are narrowed in their lengthened or extended portions, so as to form shoulders for holding the ends of the slats; or preventing them from slipping out, whereby the aid of hooks or other fastening may be, if desired, entirely dispensed with.

To enable the slats *E* to be more conveniently inserted and removed, the ends of said slats are rounded off, as shown in fig. 1.

To still further secure the connection between the rails and slats, hooks *F* may be used, which are pivoted to eyes or staples attached to the inner sides of the rails, or to the edge of the slats, and which hook into eyes or staples attached to the other of said parts, as shown in figs. 1 and 2.

Having thus described my invention,

What I claim as new, and desire to secure by Letters Patent, is—

1. The slots *D* and *D'*, formed in the inner sides of a bedstead, the latter being lengthened and also narrowed, to form shoulders for holding the contiguous ends of the slats, substantially as herein shown and described.

2. The combination of hooks *F* with the slats and grooved or slotted rails of the bedstead, substantially as herein shown and described, and for the purpose set forth.

D. M. ESTEY.
